(57) **CLAIM**

The ornamental design for a left sensor wing, as shown and described.

DESCRIPTION

FIG. 1 is a front, top, and side perspective view of the left sensor wing showing the new design.

FIG. 2 is a rear, bottom, and side perspective view of the left sensor wing showing the new design.

FIG. 3 is a top view of the left sensor wing showing the new design.

FIG. 4 is a bottom view of the left sensor wing showing the new design.

FIG. 5 is a right side view of the left sensor wing showing the new design.

FIG. 6 is a left side view of the left sensor wing showing the new design.

FIG. 7 is a front view of the left sensor wing showing the new design.

FIG. 8 is a rear view of the left sensor wing showing the new design; and,

FIG. 9 is a perspective view of the left sensor wing showing the new design within environmental structure.

The broken lines are included for the purpose of illustrating portions of the left sensor wing, as well as environment in FIG. 9, and form no part of the claimed design.

1 Claim, 9 Drawing Sheets
